CLAIM

We claim the ornamental design for a fender skirt, as shown and described.

DESCRIPTION

FIG. 1 is a front, right side perspective view of a fender skirt showing our new design, in a state of use.

FIG. 2 is an enlarged, front, right side perspective view of the fender skirt shown in FIG. 1;

FIG. 3 is a front view of the fender skirt shown in FIG. 2; FIG. 4 is a left side view of the fender skirt shown in FIG. 2;

FIG. 5 is a right side view of the fender skirt shown in FIG. 2;

FIG. 6 is a top view of the fender skirt shown in FIG. 2; and, FIG. 7 is a bottom view of the fender skirt shown in FIG. 2. The broken lines showing portions of the associated vehicle and mounting flanges of the fender skirt are for illustrative purposes only and form no part of the claimed design.

FIGS. 1-7 illustrate our novel design for the fender skirt that is suitable for use on one side of a vehicle. An opposite side fender skirt, being a mirror image thereof, is claimed but not shown.
